UNITED STATES PATENT OFFICE.

PHILIP NADELSON, OF YONKERS, NEW YORK.

LIGHT-CONCENTRATOR.

1,331,661.

Specification of Letters Patent. Patented Feb. 24, 1920.

Application filed March 22, 1919. Serial No. 284,322.

To all whom it may concern:

Be it known that I, PHILIP NADELSON, a citizen of the United States of America, residing at Yonkers, in the county of West-
5 chester and State of New York, have invented certain new and useful Improvements in Light-Concentrators, of which the following is a specification.

This invention relates to certain new and 10 useful improvements in light concentrators adapted for use in conjunction with a bowl-shaped or substantially parabolic reflector for the purpose of concentrating the light from a lamp or light source placed in said 15 reflector, whereby the rays of light are projected within certain areas.

The light from ordinary reflectors of headlights, etc., passes through the entire 180° of the arc in front of the reflector, thus 20 causing considerable glare detrimental to drivers of approaching vehicles and pedestrians, as is well known.

The primary object of the present invention is to provide a cheap and efficient means 25 for eliminating the glare of the light from headlights, searchlights or the like by eliminating substantially all of those rays of light which with the present reflectors rise above the 90° mark of an arc in front of 30 the reflector and below the 135° mark of said arc. The present invention has provision therefore to eliminate approximately 45° of the light from an ordinary reflector and concentrates, by reflecting back into 35 said ordinary reflector, those rays that are desired to be eliminated, namely, those above the 90° mark and those below the 135° mark.

With the above general objects in view and others that will become apparent as the 40 nature of the invention is better understood, the same consists in the novel form, combination and arrangement of elements herein-
after more fully described, shown in the accompanying drawing and claimed.

45 In the drawings, forming part of this specification wherein like reference characters indicate corresponding parts throughout the several views,

Figure 1 is a vertical sectional view of a 50 headlight provided with a concentrator constructed in accordance with the present invention and taken substantially upon line I—I of Fig. 2,

Fig. 2 is a front elevational view of the 55 device shown in Fig. 1 with the lens removed,

Fig. 3 is an enlarged fragmentary sectional detail view illustrating the cup for rendering the source of light invisible to the eye and its adjustable connection to the concentrator plate, 60

Fig. 4 is a central vertical sectional view of a modified form of the invention taken substantially upon line IV—IV of Fig. 5,

Fig. 5 is a front elevational view of the 65 device shown in Fig. 4,

Fig. 6 is a somewhat diagrammatic view similar to Fig. 1 drawn on a smaller scale and illustrating the use of a second small reflector and lamp in the lower portion of 70 the reflector of the main lamp,

Fig. 7 is a view similar to Fig. 6 also showing a second smaller lamp in the lower portion of the main reflector employed in conjunction with a second cup for rendering the second source of light or the smaller lamp invisible, 75

Fig. 8 is a view similar to Fig. 7 with the second smaller lamp mounted in a different position, and 80

Fig. 9 is a view similar to Fig. 1 showing a modified form of the attaching means for the concentrator plate.

Referring more in detail to the several views, the present invention contemplates 85 the modification of the reflector 5 of the usual headlight or the like to concentrate light rays within a desired area so as to eliminate glare. This object is accomplished by positioning an opaque reflecting plate 6 90 within the reflector 5 between the lens 7 and incandescent lamp 8 at an outward angle of substantially 45°, the reflecting plate or concentrator member 6 being preferably of concave or outwardly dished form with 95 its upper straight edge 9 extending entirely from side to side of the reflector 5 entirely within the plane of the transverse or horizontal diameter of the open mouth of the reflector 5. The plate 6 may be formed in 100 various ways either as an attachment for the usual reflector 5 or as an integral part thereof. However, I prefer to form the same separate from the reflector 5 and to provide the lower curved edge thereof with 105 a plurality of angularly bent lugs 10 which are arranged to flatly engage the inner surface of the reflector 5 at suitably spaced points and which are apertured to receive bolts 11 or other suitable fastening means 110 to secure the plate 6 in its operative inclined position as shown in Fig. 1. The

concave surface of the plate 6 or that surface of the same nearest the source of light 8 is preferably highly polished so that all downwardly passing direct rays from the lamp 8 are reflected to the upper portion of the reflector 5 and then pass through the upper portion of the lens 7 at a downward inclination together with the rays of light which initially pass from the source of light 8 to the upper portion of the reflector 5. In this way, very little light is lost and all of the rays are more or less reflected outwardly of the reflector 5 through the upper portion of the lens 7 to provide a concentrated brilliant beam of light so directed as to be entirely devoid of glare. In some instances, especially where high powered lamps are used, it is also necessary to provide some means for cutting off the direct rays from the lamp 8 so as to render the light source invisible. In order to accomplish this object, I provide the concentrator plate 6 with a cup 12 arranged in front of the lamp 8 substantially at or slightly above the medium line of the reflector 5 so as to be in the path of the direct rays of the lamp 8 and thereby substantially render the latter invisible. The cup 12 is preferably provided with a highly polished inner or concave face so as to reflect the direct rays of light in various paths toward the reflector 5 so as to eventually pass through the upper portion of the lens 7. As shown in Figs. 1 to 3 inclusive, the cup 12 is separate from the plate 6 and adjustably connected thereto so as to be shifted into the bowl of reflector 5 the required depth, but provided with means so that the cup may be maintained at the same height in said reflector 5. This adjustment is preferably obtained by providing the plate 6 with a pair of rows of aligned apertures 13, each row being equally spaced from the vertical center of the plate 6 and being of a size to receive the bolts 14. An angle washer 15 is placed upon each of the bolts 14 at opposite sides of the plate 6 so as to maintain the bolts 14 in a vertical position. A plurality of washers 16 are then slidably positioned upon the opposite projecting ends of the bolts 14 in contacting relation with each other and the adjacent faces of the angle washers 15. The lower ends of bolts 14 are provided with a suitable lock washer 17 and nut 18 to maintain the parts assembled and the upper end of said bolts extend through the lower edge of cup 12 in which position said cup is fastened by lock washers 19 and nuts 20. If it is desired to shift the cup 12 from its full line position as shown in Fig. 1 to its dotted line position in said figure, it is simply necessary to remove the washers 17 and 19 and nuts 18 and 20 so that the angle washers 15 and ordinary washers 16 upon the lower projecting

ends of the bolts 14 may be slidably removed and said bolts then withdrawn from the apertures 13. The bolts are then inserted in the desired apertures and some of the washers 16 placed upon the upper ends of bolts 14 that were formerly upon the lower ends thereof after which the washers 17 and 19 and nuts 18 and 20 are again placed upon the extreme ends of bolts 14 so that the cup is maintained in proper position or at the desired height and depth within the reflector 5.

As shown in Figs. 4 and 5, the plate 6' and the cup 12' may be formed from a single piece of material by a stamping and shaping or other operation, it being understood that the general form of the cup and plate in these figures is substantially the same as that of the device shown in Figs. 1 to 3 inclusive.

By disposing the plate 6 or 6' within reflector 5 at substantially an angle of 45°, an unused chamber or space 21 is provided in the lower portion of the reflector 5. As shown in Figs. 6 to 8 inclusive, this space 21 may be variously utilized to form a secondary light chamber, thus making a multiple beam lamp or headlight. In Fig. 6, this is accomplished by suitably fastening a small reflector 22 within the chamber 21, which reflector 22 is provided with a small incandescent lamp 23.

In Fig. 7, the second and small lamp 23 is shown as fastened directly to the main reflector 5 and a cup 12 smaller than but similar to the cup 12 of Fig. 1 is supported from the plate 6 so as to render the source of light or lamp 23 invisible.

Substantially the same construction as shown in Fig. 7 is also shown in Fig. 8 with the exception that the small lamp 23, may, as shown, be fastened to or mounted on the plate 6 instead of to or on the reflector 5, a cup 12 for rendering the lamp 23 invisible being also shown in this figure as supported from the plate 6.

The secondary lamp in Figs. 6 to 8 inclusive is often desirable when only a slight amount of light is required and will be found useful in various other respects.

The present invention will be found useful on automobile, motorcycle, train, car, boat or other lights, and while the form of the plate 6 is herein shown and described as concave it is obvious that the same may be otherwise shaped and still provide more or less efficient results in accordance with the objects of the invention.

It is believed that the construction and operation of the present invention will be readily understood from the foregoing description by those skilled in the art and while the forms of the invention herein shown and described are what are believed to be the preferable embodiments thereof,

it is nevertheless to be understood that minor changes may be made in the form, arrangement and combination of parts without departing from the spirit and scope of the invention as claimed.

In Fig. 9, the plate 6 is shown as provided with a tab or extension 24 which is curved to lie against the inner face of the reflector 5 and which is extended upwardly from the lower edge of said plate 6. The free end of the tab 24 is apertured for reception on the base —a— of the lamp 8 whereby the device is suspended in the operative position shown, and in order to secure the same against shaking or other movement, a collar 25 is slid onto the base —a— and secured by a set screw 26 so as to firmly clamp the end of the extension 24 against the reflector 5.

The term "at an outward angle" is herein used to denote the arrangement of the plate 6 or 6' with its free edge 9 nearer the lens 7 and the axis of the reflector 5 than the other edge thereof so that the plate is positioned as shown in Fig. 1 in front of the light source 8.

What I claim as new is:—

1. A concentrator attachment for headlight or other concaved reflectors having a source of light comprising a substantially semicircular plate adapted for attachment to an ordinary reflector so as to be disposed therein at an outwardly and upwardly extending angle of substantially 45° , said plate being provided with a reflecting inner surface, and a cup associated with said plate arranged to render the source of light invisible, said cup being adjustable toward and away from the source of light without varying the height thereof.

2. A concentrating attachment for substantially parabolic reflectors and adapted to substantially close one-half of the latter comprising a substantially semicircular plate adapted for attachment to and within

said reflector at an angle and provided with vertically aligned perforations therein adjacent the vertical center thereof, a reflecting concave cup, a bolt detachably fastened thereto, and means to fasten said bolt and cup to said plate with the bolt extending through a desired one of said perforations whereby the bolt may be adjusted through said perforations to vary the height of said cup relative to the plate.

3. A concentrating attachment for substantially parabolic reflectors and adapted to substantially close the lower half of the latter comprising a substantially semicircular plate adapted for attachment to and within said reflector at an angle and provided with vertically aligned perforations therein adjacent the vertical center thereof, a reflecting concave cup, a bolt detachably fastened thereto, and means to fasten said bolt and cup to said plate with the bolt extending through a desired one of said perforations whereby the bolt may be adjusted through said perforations to vary the height of said cup relative to the plate, said means including ordinary washers and a pair of angle washers adapted for slidable reception by and upon said bolt.

4. The combination with a substantially parabolic reflector having a light source centrally positioned therein, of a concentrator plate arranged within said reflector at an outward angle of substantially 45° and being of a size to prevent the light of said source from passing through substantially an entire one half of the headlight lens whereby an unused chamber is provided in a portion of said reflector forwardly of the concentrator plate, a second light source positioned within said chamber, and a cup supported by said plate within said chamber to render the second source of light invisible.

In testimony whereof I affix my signature.
PHILIP NADELSON.
